US0D1017543S

(12) **United States Design Patent** (10) Patent No.: **US D1,017,543 S**
(45) Date of Patent: ** Mar. 12, 2024

(54) **CHARGING STATION FOR ROBOT**

(71) Applicants: **WeHome Technology Company Limited**, Hong Kong (CN); **Fuzhi Technology (Shenzhen) Co., Ltd.**, Shenzhen (CN)

(72) Inventors: **Xiaoting Wu**, Shenzhen (CN); **Shujian Yuan**, Shenzhen (CN); **Yingsheng Mahe**, Shenzhen (CN)

(**) Term: **15 Years**

(21) Appl. No.: **35/515,860**

(22) Filed: **Nov. 24, 2022**

(80) **Hague Agreement Data**

Int. Filing Date: **Nov. 24, 2022**

Int. Reg. No.: **DM/225547**

Int. Reg. Date: **Nov. 24, 2022**

Int. Reg. Pub. Date: **Dec. 23, 2022**

(51) LOC (14) Cl. **13-02**

(52) U.S. Cl.

USPC **D13/108**

(58) **Field of Classification Search**

(57) **CLAIM**

The ornamental design for a charging station for robot, as shown and described.

DESCRIPTION

1. Charging station for robot
1.1 : Perspective
1.2 : Perspective
1.3 : Front
1.4 : Back
1.5 : Right
1.6 : Left
1.7 : Top
1.8 : Bottom
1.9 : Top view in state of variation
1.10 : Perspective view in state of variation
The broken lines depict portions of the charging station for robot that form no part of the claimed design.

1 Claim, 10 Drawing Sheets
